DISCHARGE TUBE

Gunther Jobst and Hans Otto Roosenstein, Berlin, Germany, assignors to Telefunken Gesellschaft fur Drahtlose Telegraphie m. b. H., Berlin, Germany, a corporation of Germany

Application February 6, 1933, Serial No. 655,354
In Germany January 30, 1932

3 Claims. (Cl. 250—20)

Tubes have become known in the prior art, known as of the variable 1:mu type whose discharge characteristic for high negative biasing potentials, have a shape coming close to the abscissa axis. The practical use of such tubes, inter alia, is to secure volume control in radio frequency amplifier tubes or rectifier stages for radio receivers inside relatively wide limits by the choice of suitable grid bias potentials without unduly much distortion being incidentally occasioned.

In the past it has never been sufficiently taken into consideration that when working at different points of the characteristic, inside the working range, the distortion must be constant; on the contrary, in the case of the tubes heretofore employed the distortion at some points was disproportionately higher than at other points inside the operating range.

Rectifier arrangements are also known in the art whose rectifying characteristic obeys a logarithmic law and which have the property that the reproducing intensity of modulation is independent of the mean of the radio frequency, indeed, dependent upon only the degree of modulation of the carrier wave. Circuit schemes of this kind, inter alia, provide for the use of tubes whose static characteristics obey in some definite manner a logarithmic law in such a way that from a definite grid biasing potential the discharge current grows in accordance with a logarithmic law. A characteristic of this kind presupposes, as shown in Fig. 1, a curve which presents a concavity towards the grid voltage axis (abscissa axis) which often is designated as a convex curve

$$\left(\frac{d^2y}{dx^2} > 0 \right)$$

Since with decreasing currents no adherence close to the abscissa axis takes place as is peculiar to all thermionic discharge actions it is hard to realize the same even in approximation.

The invention discloses a type of tube suited both for radio frequency amplification as well as radio frequency rectifier work whose characteristic is so chosen that, on the one hand, if the grid biasing potential is properly chosen, it insures volume control attended throughout the entire range of regulation with only small constant distortions so that the quality of reproduction remains constant throughout the entire control range; on the other hand, realization of such a characteristic is readily feasible with simple means, for instance, variable 1:mu. Screen grid

type tubes will be used most suitably inasmuch as in these amplification is insurable without plate reaction so that it is directly proportional to the slope or mutual conductance of the tube for all points. The characteristic of a tube according to this invention, inside the working range, obeys likewise a logarithmic law, though being convex in reference to the abscissa axis.

Fig. 2 shows a characteristic curve approximating curves of actual tubes and also corresponding to the function

$$i_p = -A \log e_{grid}$$

where A is an always positive constant. The voltage fed to the grid is

$$e_{go} + e_g \sin t$$

where e_{go} is the grid biasing potential and e_g is the amplitude of the radio frequency wave-train. What should be taken into consideration in this connection is the necessity of a negative sign of the log. which manifests itself by a convex curvature toward the abscissa axis as required according to what has been pointed out above.

Introducing in the value for e_{grid} the current function, then:

$$J = -A \log (-e_{go} - e_g \sin t)$$

or if e_g is placed outside the brackets, this equation is obtained:

$$J = -A \log (-e_{go}) - A \log \left(1 + \frac{e_g}{e_{go}} \sin t \right)$$

Now, if e_{go} , the biasing potential, be so set that its value becomes proportional to the amplitude of the radio frequency, then on basis of the requirement that

$$\frac{e_g}{e_{go}} = c$$

this formula is found

$$J = -A \log (-e_{go}) - A \log (1 + c \sin t)$$

In this equation the first term is a quantity wholly independent of radio frequency, but a function of the mean amplitude which bears no influence at all upon the amplification process. The second quantity is not dependent upon the amplitude of radio frequency, whence the conclusion that the radio frequency output of the tube is not only independent of the input amplitude, but that also the quality of reproduction will always remain the same, and this for the reason that the expression $(1 + c \sin t)$ does not include a quantity being a function of the variations in the input oscillations. If c be chosen

sufficiently small, as to the rest, the distortion may be kept within bounds, and the expression

$$\log_e (1+c \sin t)$$

simply changes into

$$c \sin t.$$

The discharge characteristic indicated by (1), inside certain limits, is representable by a characteristic which comes close to the presupposed negative logarithmic law.

In Fig. 3 the function

$$15 \quad -A \log \left(\frac{-z+a}{b} \right)$$

is represented with its differential quotients. The significance of quantities A , a , and b can be seen with sufficient clearness from Fig. 3. They are governed by the conditions of maximum slope S (mutual conductance)

$$\delta_{\max.} \text{ for } z=0, \delta_{\min.} \text{ for } z=z_{\max.}$$

and the size of the range of modulation $z=z_{\max.}$ in such a way that

$$\frac{A}{a} = S_{\max.} (z=0); \frac{A}{b} = S_{\min.}, (z=z_{\max.}) Z_{\max.} = -b + a.$$

30 Putting again

$$z = e_{go} + e_g \sin t$$

there becomes

$$35 \quad J = -A \log \frac{-e_{go} - e_g \sin t + a}{b}$$

or

$$J = A \log b - A \log (-e_{go} + a) - A \log \left(1 - \frac{e_g \sin t}{e_{go} + a} \right).$$

40 Suppose, then, that

$$\frac{e_g}{-e_{go} + a} = c, \text{ or } e_{go} = \frac{e_g}{-c + a}$$

45 where a substantially is fixed by the maximum slope (mutual conductance) obtainable for $z=0$. c further can be fixed so that, with adequate distribution a small enough distortion will be obtained. However, there is one condition that imposes a limitation upon c , namely as follows: The grid voltage, i. e., the sum total of grid biasing potential and grid alternating potential should never extend beyond $z=0$ towards the right-hand side 50 lest damping be caused by the incipient grid current, and because the presupposed law, as will be noted, no longer holds true outside the regulating range, that is to say, when $z>0$. An additional condition therefore is

$$60 \quad e_{go} + e_g \leq 0.$$

Combining this equation with the last equation, this formula follows:

$$65 \quad e_{go} + e_g = e_g \left(1 - \frac{1}{c} \right) + a \leq 0$$

which after a few transformations results in this value for c

$$\frac{e_g}{e_g + a} \text{ or } c \max. = \frac{e_g \min.}{e_g \min. + a}$$

70 In other words, the value of the output currents is governed by the smallest still controllable grid alternating potential and the quantity a . c will be so much larger, the larger l_g , and it may become equal to unity for sufficiently large $l_{g\min.}$ or for

$a=c$. Or, if in the equation the explicit value for a is introduced there follows:

$$c \max. = \frac{e_g \min.}{(Z \max.) \delta \min.} \approx$$

$$e_g \min. + \frac{\max. - \delta \min.}{\delta \min.}$$

$$\frac{e_g \min.}{e_g \min. + Z \max.} \frac{(\delta \min.)}{\delta \max.}$$

Upon the side of the output currents of such an arrangement limitations are imposed which are determined by the lowest occurring amplitude $l_{g\min.}$, by the regulation range $Z \max.$ and regulability ($\delta \max. : \delta \min.$). 10

The characteristic thus fixed is realizable between $z=0$ and $z=z_{\max.}$. The non-realizable points, that is, to the right of $z=0$ and left of $z=z_{\max.}$, since they are located outside the working range, deserve no interest so far as the working of the characteristic is concerned. Whatever may be the shape of the characteristics in that range, the operation of the tube will thereby never be impaired. 15

Under practical conditions, it is permissible to deviate, inside certain limits, from the given negative logarithmic law without causing an incidental impairment of the effect or result. These deviations suitably are referred to the deviations of the first differential quotients, the characteristic, which represent the slope and thus the amplification of the tube. Fig. 4 shows a circuit arrangement in which a tube according to this invention has in its grid circuit a voltage proportional to the input amplitude of the oscillations to be received. 40

A designates the antenna, E the input circuit of the radio frequency tube H whose control electrode is impressed at Q with the amplitudes of the incoming oscillations. G denotes the audion in whose output circuit is indicated the reproducer device T. By way of a separate rectifier circuit D, after suitable amplification, there is obtained a current resulting in the biasing voltage of the amplifier tube H. 45

What we claim is:

1. In a radio receiver provided with a radio frequency amplifier stage having a tuned input circuit, an electron discharge tube in said stage having a control grid potential-plate current characteristic which is logarithmic over a range of control grid potentials extending to at least -20 volts, a vacuum tube rectifier for developing a biasing potential for the control grid of said amplifier which is proportional to the carrier amplitude of received signal waves, said biasing potential being developed across a resistor which is connected in series in the grid circuit of said amplifier and also in series in the plate circuit of said rectifier. 55

2. In a radio receiver provided with a radio frequency amplifier and a detector, an automatic volume control arrangement for maintaining the signal input to the detector substantially constant regardless of fading of received signal waves, said arrangement including a rectifier tube provided with a resistor in its output circuit to develop a negative biasing voltage for the amplifier signal 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

grid which is proportional to the amplitude of the signal waves, means for applying said biasing voltage to said signal grid, said amplifier being provided with a tube having a grid voltage-plate current characteristic such that the plate current varies as the log of the grid voltage over a relatively wide range of negative grid voltages.

5. An arrangement for amplifying radio frequency currents comprising the combination of an electron discharge tube having a cathode, a control grid, an anode and a screen grid located between said anode and control grid, an input cir-

cuit connected to said control grid and cathode, an output circuit connected to said anode, means for impressing modulated signal currents on said input circuit and means for varying the bias voltage of said control grid, the elements within said tube being constructed so that $i_p = -A \log e_g$, wherein

A is a positive constant

i_p = value of plate current

e_g = value of signal voltage applied to grid.
